SAFETY FISHHOOK HOLDER

Frank Woodhead, Collingdale, Pa.

Application December 20, 1948, Serial No. 66,299

14 Claims. (Cl. 43—57.5)

1

This invention relates to safety fish-hook holders and has as its object the production of a new and improved article of this class.

More particularly stated one of the objects of this invention is to produce a safety fish-hook holder which will be comparatively simple in structure and wherein the hooks will be positively latched in place.

Another of the objects of this invention is to produce a safety fish-hook holder with positive latching means for the fish-hooks which will be comparatively simple in structure and into which one will be able to insert the hooks and from which one will be able to remove the hooks with comparative ease.

Another of the objects of this invention is to produce a safety fish-hook holder with positive latching means for the fish-hooks which will be comparatively simple in structure, which will house the leaders, and into which one will be able to insert the leaders and from which one will be able to remove the leaders with comparative ease when the latching hood is either in its latched or unlatched position.

I attain the foregoing as well as other objects by forming a hook carrying and housing member, providing same with a leader receiving chamber, providing said leader receiving chamber with an entry and exit corridor, mounting a latching hood on said hook carrying and housing member for movement to a hook latching and to a hook unlatching position, and providing said latching hood with means which will normally exert a force for holding said latching hood in its latched position.

For the purpose of disclosing the invention with the particularity required by law I have shown in the drawings which form a part hereof and will now describe a few of the many possible embodiments of my inventive concepts.

In said drawings

Figure 1 is a side view of an embodiment of the invention. The latching hood is shown in its raised or unlatched position. A portion of the latching hood has been broken away to show otherwise hidden parts.

Figure 2 is a plan view looking in the direction of the arrow A in Figure 1.

Figure 3 is a bottom view looking in the direction of the arrow B in Figure 1.

Figure 4 is a side view of the embodiment shown in Figure 1 with the latching hood in its depressed or latched position. The latching hood is shown in section and a portion of the hook carrying and housing member has been broken away to show otherwise hidden parts.

2

Figure 5 shows the unit in the latching position shown in Figure 4 held in the hands of a user who may be considered in the act of removing a leader from the housing or inserting same therein.

Figure 6 is a side view of another embodiment of the invention with the latching hood in its raised or unlatched position. A portion of the hook carrying and housing member and latching hood has been broken away to show otherwise hidden parts. A fragment of the latching hood is shown in section.

Figure 7 is a bottom view looking in the direction of the arrow C in Figure 6 with the latching hood removed.

Figure 8 is a side view of the upper fragment of still another embodiment of the invention with the latching hood in its depressed or latched position. The housing cylinder and latching hood are shown in section. A portion of the spring and latching hood piston housing tube has been broken away to show otherwise hidden parts.

Figure 9 is a side view of the latching hood and its bearing member, two of the component elements of the modification of the unit shown in Figure 8 detached from the remainder of the hook carrying and housing member. The latching hood is shown in section and a portion of the spring and latching hood piston housing tube has been broken away to show otherwise hidden parts.

Figure 10 is a bottom view looking in the direction of the arrow D in Figure 8 with the hook carrying and housing member shown in section.

Figure 11 is a section taken on the line 11—11 of Figure 8.

Figure 12 is a section of a fragment taken along the line 12—12 of Figure 11.

Referring more particularly to the drawings, wherein similar reference numerals denote similar parts, reference numeral 1 designates the safety fish-hook holder shown in Figures 1 to 5 as a unit.

The safety fish-hook holder 1 consists of a hook carrying and housing member 2, a latching hood 3 movably mounted on said hook carrying and housing member 4 for assuming either a hook latching or hook unlatching position, and a spring 4 positioned for impelling said latching hood to assume its hook unlatching position.

The hook carrying and housing member 2 is a hollow cylinder the walls 5 of which bound and form the chamber 6 and cut out at places to form the openings 7. The openings 7 lighten the weight of the hook carrying and housing member and also permit a portion of the leaders 30 at-

tached to the fish-hooks 29 to be received within said chamber 6. The hook carrying and housing member 2 has formed thereon near the lower end thereof a rectangular flange 8 which prevents fish-hook holder 1 from rolling. Said flange 8 and the cylindrical wall 5 of said hook carrying and housing member 2 have four angular slots 9 formed therein which permit the leaders 30 to be inserted easily into the chamber 6. The upper ends 11 and lower ends 12 of each of the bounding walls 10 of each of said angular slots 9 are curved outwardly. These curved ends 11 and 12 serve to prevent the leaders from too readily leaving the chamber 6 through the said slots 9. The cylindrical wall 5 of the hook carrying and housing member 2 also has formed therein near the upper end thereof a plurality of vertical fish-hook receiving slots 13. The lower end of each of said fish-hook receiving slots 13 terminates at a circular hook supporting ledge 14 which is formed on said hook carrying and housing member 2. The cylindrical wall 5 of said hook carrying and housing member 2 has formed therein two identical diametrically opposed bayonet slots 15 each consisting of a vertical portion 16 terminating in a horizontal portion 17 which in turn terminates in a substantially semicircular portion 18. The hook carrying and housing member 2 has mounted therein near the upper end thereof a spring supporting platform 19 which serves as a support for the lower end 21 of the spring 4. The upper end 20 of the spring 4 encircles a suitable pintle 34 which extends downwardly from the roof 24 of the latching hood 3.

The latching hood 3 consists of a hollow cylindrical body member 22 having the cylindrical wall 23, the roof 24 and the circular latching brim 25. The wall 23 and the roof 24 define a chamber 33. The curvature of the inner surface 26 of the wall of the latching brim 25 is substantially parallel to that of the outer surface 27 of the hook supporting ledge 14 and spaced therefrom a distance slightly greater than the diameter or thickness of the fish-hooks 29, which the safety fish-hook holder 1 is designed to hold. The curvature of said surfaces 26 and 27 is substantially that of the fish-hooks 29 which the safety fish-hook holder 1 is designed to hold. The latching hood 3 has attached thereto the pin 28 which extends through bayonet slots 15 and across the upper end of the chamber 6.

It is believed to be obvious from said drawings and the foregoing description that in order to insert fish-hooks into the safety fish-hook holder one starts with said holder in the position shown in Figure 1. Then one positions any desired number of fish-hooks 29 upon the hook supporting ledge 14. Then one pushes the latching hood 3 downwardly against the pressure of the spring 4 in the direction of the arrow A in Figure 1 until the pin 28 reaches the horizontal portion 17 of the bayonet slot 15. At this point one turns the latching hood 3 in a clockwise direction until the pin reaches the far end of the horizontal portion 17 of the bayonet slot 15. Then one releases slightly the downward pressure on the latching hood 3. This permits the spring 4 to force said latching hood upwardly the slight distance necessary to cause the latching pin 28 to be received within the semi-circular latching groove 18 thereby latching the fish-hooks 29 in place. This position is illustrated in Figures 4 and 5. The pressure of the spring 4 positively holds the latching pin 28 and latching hood 3 to which 75

said latching pin is attached in said latching position. Although the lower ends of the leaders 30 may be inserted into the chamber 6 through the slots 9 when the latching hood is in the position shown in Figure 1 yet I prefer to do so when the latching hood is in the position shown in Figures 4 and 5. To remove any hook from the safety fish-hook holder 1 one holds the unit in the position shown in Figure 5 and removes the leader 30 of the desired hook from the chamber 6 by moving same from the slot 9. Then one pushes the latching hood 3 downwardly in the direction of the arrow E in Figures 4 and 5 and turns same in the counter-clockwise direction until it reaches the near end of the horizontal slot 17 of the bayonet slot 15 and releases the pressure on said latching hood with the result that the latching hood 3 moves from the position shown in Figures 4 and 5 to that shown in Figure 1. In this position the pressure of the spring 4 also positively holds the latching hood 3 in its unlatched position thereby enabling the user the freest use of his hands in positioning fish-hooks upon said hook supporting ledge 14 and removing them therefrom. At this point one removes the hook or hooks selected and then proceeds to latch the remaining hooks in the manner hereinabove specified by pushing the latching hood downwardly turning same in the clockwise direction until it reaches the far end of the horizontal slot 16, and slightly releasing the pressure on the latching hood.

The safety fish-hook holder 41 shown in Figures 6 and 7 consists of the hook carrying and housing member 42, the latching hood 43 and the latching hood actuating and latching spring 44.

The hook carrying and housing member 42 shown in Figures 6 and 7 differ from the hook carrying and housing member shown in Figures 1 to 5 in the following particulars:

(1) Four spaced fins 45 have been substituted for the rectangular flange 8.

(2) The fish-hook receiving slots 48 extend downwardly from the upper edge 47 of the cylindrical wall 46 instead of being formed below said edge.

(3) The spring receiving cylindrical tube 49 having the fins 50 extending therefrom and closed at its lower end 51 have been substituted for the spring supporting platform 19. Each of the fins 50 is attached to the inner surface 52 of the cylindrical wall 46.

(4) Two identical oppositely disposed bayonet slots 53 are formed in the cylindrical wall 54 of the cylindrical tube 49. The bayonet slots 53 are identical in structure and function with the bayonet slots 15 shown in Figures 1 to 5.

The latching hood latching and actuating spring 44 shown in Figures 6 and 7 differs from its counterpart 4 shown in Figures 1 to 5 in shape.

The latching hood 43 shown in Figures 6 and 7 differs from the latching hood shown in Figures 1 to 5 in the following particulars:

(1) Its cylindrical wall 55 is not as high as the cylindrical wall 23 of the latching hood 3.

(2) The tubular chamber 56 formed in said latching hood 43 has a greater diameter than that of the chamber 33 formed in said latching hood 3. The diameter of the hook carrying and housing member 42 is greater than the diameter of the hook carrying and housing member 2.

(3) The spring contacting piston 57 has been substituted for the spring receiving pintle 34.

(4) The latching pin 58 which extends through

the bayonet slots 53 and spring contacting piston is shorter than the latching pin 28.

The safety fish-hook holder 61 shown in Figures 8 to 12 differs from that shown in Figures 6 and 7 in the following particulars:

(1) The spring receiving tube 63 and the fins 64 extending therefrom which together form the latching hood supporting member 62 have been substituted for the spring receiving tube 49 and fins 50.

(2) Each of the fins 64 has formed thereon a resilient finger 65 which terminates in a latching lug 66.

The hook carrying and housing member 67 differs from the hook carrying and housing member 42 in the following particulars:

(1) The inner surface 69 of the cylindrical wall 68 of the hook carrying and housing member 67 have formed therein the oppositely disposed identical slots 70 which receive and hold the free edges 71 of the fins 64.

(2) The cylindrical wall 68 of the hook carrying and housing member 67 has formed therein near the lower end of each of said slots 70 an aperture 72 which receives the latching lug 66 on the finger 65 contiguous thereto.

To assemble the unit 61 one first assembles the latching hood 43 with the latching hood supporting member 62 by positioning the latching hood actuating spring 44 within the chamber 59 of the spring receiving tube chamber 63, then positioning the spring contacting piston 51 of the latching hood 43 within said spring receiving chamber 59, then forcing the latching pin 58 through the suitable aperture formed in said spring contacting piston 51 and through the oppositely disposed bayonet slots 53 and upsetting the ends of said latching pin 58 to hold same in place. Then one inserts the unit so assembled within the chamber 67 of the hook carrying and housing member 66. In so doing one exerts the pressure necessary upon the latching fins 64 necessary to spring said latching fins a distance inwardly sufficient to permit the latching fingers 65 and latching lugs 66 which they carry to be received within the chamber 67. Then one manipulates the unit so that the free edges 71 of the fins 65 enter the slots 70. The unit is then moved downwardly until the latching lugs 66 reach the apertures 72. At that point the latching lugs 66 enter said recesses being forced to do so by the pressure of the compressed latching fingers 65. This latches the unit firmly in place.

The foregoing description is to be understood as being for the purpose of illustration only and not limitation since many changes may be made in the structures herein shown without departing from the spirit of my invention.

Having described my invention what I claim as new and useful is:

1. A safety fish-hook holder consisting of a hook carrying and housing member having hook receiving slots formed therein; a hook supporting ledge positioned on said hook carrying and housing member at the floor of said hook receiving slots; a latching hood mounted on said hook carrying and housing member for movement to a hook latching and to a hook unlatching position; a latching brim carried by said latching hood and positioned for cooperating with said hook supporting ledge to latch said fish-hooks upon said fish-hook holder when said latching hood is in its hook latching position; co-operating slot and pin latching means carried by said hook carrying and housing member and by said latching hood;

and resilient means reactively supported by both said hook carrying and housing member and said latching hood for holding said latching hood in its latched position.

5. A safety fish-hook holder consisting of a hook carrying and housing member having hook receiving slots formed therein; a leader receiving chamber formed in said hook carrying and housing member; a hook supporting ledge positioned on said hook carrying and housing member at the floor of said hook receiving slots; a latching hood mounted on said hook carrying and housing member for movement in a vertical direction to a hook latching and to a hook unlatching position; a latching brim carried by said latching hood and positioned for cooperating with said hook supporting ledge to latch said fish-hooks upon said fish-hook holder when said latching hood is in its hook latching position; co-operating slot and pin latching means carried by said hook carrying and housing member and by said latching hood; and resilient means reactively supported by both said hook carrying and housing member and said latching hood for holding said latching hood in its latched position.

3. A safety fish-hook holder consisting of a hook carrying and housing member having hook receiving slots formed therein; a hook supporting ledge positioned on said hook carrying and housing member at the floor of said hook receiving slots; a leader receiving chamber formed in said hook carrying and housing member; there being an entry and exit slot formed in said leader receiving chamber; a latching hood mounted on said hook carrying and housing member for movement in a vertical direction to a hook latching and to a hook unlatching position; a latching brim carried by said latching hood and positioned for cooperating with said hook supporting ledge to latch said fish-hooks upon said fish-hook holder when said latching hood is in its hook latching position; co-operating slot and pin latching means carried by said hook carrying and housing member and by said latching hood; and resilient means reactively supported by both said hook carrying and housing member and said latching hood for holding said latching hood in its latched position.

4. A safety fish-hook holder consisting of a hook carrying and housing member having hook receiving slots formed therein in the upper part thereof, having at least one bayonet slot formed therein, and a leader receiving chamber formed in the lower part thereof there being a plurality of cut outs formed in said leader receiving chamber forming open windows therein; a hook supporting ledge positioned on said hook carrying and housing member at the floor of said hook receiving slots; a spring supporting platform carried by said hook carrying and housing member; a latching hood mounted on said hook carrying and housing member for movement to a hook latching and to a hook unlatching position; a latching brim carried by said latching hood and positioned for cooperating with said hook supporting ledge to latch said fish-hooks upon said fish-hook holder when said latching hood is in its hook latching position; a latching pin carried by said latching hood and positioned for movement in said bayonet slot; and a latching hood latching spring positioned at its lower end on said spring supporting platform and contacting the roof of said latching hood at its upper end.

5. A safety fish-hook holder consisting of a hook carrying and housing member having hook

receiving slots formed therein in the upper part thereof and a leader receiving chamber formed in the lower part thereof, there being a plurality of cut outs formed in said leader receiving chamber forming open windows therein; a hook supporting ledge positioned on said hook carrying and housing member at the floor of said hook receiving slots; a non-circular flange carried by said hook carrying and housing member near the lower end of said leader receiving chamber; an entry and exit slot formed in said leader receiving chamber and non-circular flange, the upper end of one of the bounding walls of each of said entry and exit slots and the lower end of each of the other of said bounding walls being curved outwardly; said hook carrying and housing member being provided with a bayonet slot; a latching hood latching spring supporting platform carried by said hook carrying and housing member; a latching hood mounted on said hook carrying and housing member for movement to a hook latching and to a hook unlatching position; a latching brim carried by said latching hood and positioned for cooperating with said hook supporting ledge to latch said fish-hooks upon said fish-hook holder when said latching hood is in its hook latching position; a latching pin carried by said latching hood and positioned for movement in said bayonet slot; a latching hood latching spring engaging pintle carried by said latching hood; and a latching hood latching spring positioned at its lower end on said latching hood latching spring supporting platform and at its upper end engaging the lower end of said pintle.

6. A safety fish-hook holder consisting of a hook carrying and housing member having hook receiving slots formed therein in the upper part thereof and a leader receiving chamber formed in the lower part thereof there being a plurality of cut outs formed in said leader receiving chamber forming open windows therein; a hook supporting ledge positioned on said hook carrying and housing member at the floor of said hook receiving slots; a spring receiving tube having formed therein at least one bayonet receiving slot and having fins extending therefrom carried by said hook carrying and housing member; a latching hood mounted on said hook carrying and housing member for movement to a hook latching and to a hook unlatching position; a latching brim carried by said latching hood and positioned for cooperating with said hook supporting ledge to latch said fish-hooks upon said fish-hook holder when said latching hood is in its hook latching position; a latching pin carried by said latching hood and positioned for movement in said bayonet slot; and a latching hood latching spring positioned within said spring receiving tube.

7. A safety fish-hook holder consisting of a hook carrying and housing member having hook receiving slots formed therein in the upper part thereof and a leader receiving chamber formed in the lower part thereof; a plurality of external fins formed on said hook carrying and housing member; there being a plurality of cut outs formed in said leader receiving chamber forming open windows therein; a hook supporting ledge positioned on said hook carrying and housing member at the floor of said hook receiving slots; a spring receiving tube having formed therein at least one bayonet receiving slot and having fins extending therefrom carried by said hook carrying and housing member; a latching hood mounted on said hook carrying and housing

member for movement to a hook latching and to a hook unlatching position; a latching brim carried by said latching hood and positioned for cooperating with said hook supporting ledge to latch said fish-hooks upon said fish-hook holder when said latching hood is in its hook latching position; a latching pin carried by said latching hood and positioned for movement in said bayonet slot; and a latching hood latching spring positioned within said spring receiving tube.

8. A safety fish-hook holder consisting of a hook carrying and housing member having hook receiving slots formed therein in the upper part thereof and a leader receiving chamber formed in the lower part thereof; a plurality of external fins formed in said hook carrying and housing member; there being a plurality of cut outs formed in said leader receiving chamber forming open windows therein; a hook supporting ledge positioned on said hook carrying and housing member at the floor of said hook receiving slots; a spring receiving tube having formed therein at least one bayonet receiving slot and having fins extending therefrom carried by said hook carrying and housing member; an entry and exit slot formed in said leader receiving chamber; a latching hood mounted on said hook carrying and housing member for movement to a hook latching and to a hook unlatching position; a latching brim carried by said latching hood and positioned for cooperating with said hook supporting ledge to latch said fish-hooks upon said fish-hook holder when said latching hood is in its hook latching position; a latching pin carried by said latching hood and positioned for movement in said bayonet slot; and a latching hood latching spring positioned within said spring receiving tube and engaging pintle at its upper end.

9. A safety fish-hook holder consisting of a tubular hook carrying and housing member having hook receiving slots formed therein in the upper part thereof and a leader receiving chamber formed in the lower part thereof there being a plurality of cut outs formed in said leader receiving chamber forming open windows therein; a hook supporting ledge positioned on said hook carrying and housing member at the floor of said hook receiving slots; there being a pair of oppositely disposed fin receiving channels formed on the inner face of the wall of said hook carrying and housing member; a spring receiving tube having formed therein at least one bayonet receiving slot; two spaced fins each attached to said spring receiving tube at one of its ends and positioned within one of said fin receiving channel at the other of its ends; a latching hood mounted on said hook carrying and housing member for movement to a hook latching and to a hook unlatching position; a latching brim carried by said latching hood and positioned for cooperating with said hook supporting ledge to latch said fish-hooks upon said fish-hook holder when said latching hood is in its hook latching position; a latching pin carried by said latching hood and positioned for movement in said bayonet slot; and a latching hood latching spring positioned within said spring receiving tube.

10. A safety fish-hook holder consisting of a tubular hook carrying and housing member having hook receiving slots formed therein in the upper part thereof and a leader receiving chamber formed in the lower part thereof; a plurality

of external fins formed on said hook carrying and housing member; there being a plurality of cut outs formed in said leader receiving chamber forming open windows therein; a hook supporting ledge positioned on said hook carrying and housing member at the floor of said hook receiving slots; there being a pair of oppositely disposed fin receiving channels formed on the inner face of the wall of said hook carrying and housing member; a spring receiving tube having formed therein at least one bayonet receiving slot; two spaced fins each attached to said spring receiving tube at one of its ends and positioned within one of said fin receiving channels at the other of its ends; a latching hood mounted on said hook carrying and housing member for movement to a hook latching and to a hook unlatching position; a latching brim carried by said latching hood and positioned for cooperating with said hook supporting ledge to latch said fish-hooks upon said fish-hook holder when said latching hood is in its hook latching position; a latching pin carried by said latching hood and positioned for movement in said bayonet slot; and a latching hood latching spring positioned within said spring receiving tube.

11. A safety fish-hook holder consisting of a tubular hook carrying and housing member having hook receiving slots formed therein in the upper part thereof and a leader receiving chamber formed in the lower part thereof; there being a plurality of cut outs formed in said leader receiving chamber forming open windows therein; a hook supporting ledge positioned on said hook carrying and housing member at the floor of said hook receiving slots; there being a pair of oppositely disposed fin receiving channels formed on the inner face of the wall of said hook carrying and housing member; a spring receiving tube having formed therein at least one bayonet receiving slot positioned within said hook carrying and housing member; two spaced fins each attached to said spring receiving tube at one of its ends and positioned within one of said fin receiving channels at the other of its ends; a latching finger attached to each of said fins attached to said spring receiving tube and positioned in one of said fin receiving channels; a latching hood mounted on said hook carrying and housing member for movement to a hook latching and to a hook unlatching position; a latching brim carried by said latching hood and positioned for cooperating with said hook supporting ledge to latch said fish-hooks upon said fish-hook holder when said latching hood is in its hook latching position; a latching pin carried by said latching hood and positioned for movement in said bayonet slot; and a latching hood latching spring positioned within said spring receiving tube.

12. A safety fish-hook holder consisting of a tubular hook carrying and housing member having hook receiving slots formed therein in the upper part thereof and a leader receiving chamber formed in the lower part thereof there being a plurality of cut outs formed in said leader receiving chamber forming open windows therein; a hook supporting ledge positioned on said hook carrying and housing member at the floor of said hook receiving slots; there being a pair of oppositely disposed fin receiving channels formed on the inner face of the wall of said hook carrying and housing member; there being a fin latching aperture formed in the wall of said hook carrying and housing member near the lower end of each of said fin receiving channels; a spring receiving

tube having formed therein at least one bayonet receiving slot positioned within said hook carrying and housing member; two spaced fins each attached to said spring receiving tube at one of its ends and positioned within one of said fin receiving channels at the other of its ends; a latching finger attached to each of said fins attached to said spring receiving tube and positioned in one of said fin receiving channels; a latching pintle formed on each of said latching fingers and positioned within one of said fin latching apertures; a latching hood mounted on said hook carrying and housing member for movement to a hook latching and to a hook unlatching position; a latching brim carried by said latching hood and positioned for cooperating with said hook supporting ledge to latch said fish-hooks upon said fish-hook holder when said latching hood is in its hook latching position; a latching pin carried by said latching hood and positioned for movement in said bayonet slot; and a latching hood latching spring positioned within said spring receiving tube.

13. A safety fish-hook holder consisting of a tubular hook carrying and housing member having hook receiving slots formed therein in the upper part thereof and a leader receiving chamber formed in the lower part thereof, a plurality of external fins formed on said hook carrying and housing member; there being a plurality of cut outs formed in said leader receiving chamber forming open windows therein; a hook supporting ledge positioned on said hook carrying and housing member at the floor of said hook receiving slots; there being a pair of oppositely disposed fin receiving channels formed on the inner face of the wall of said hook carrying and housing member; a spring receiving tube having formed therein at least one bayonet receiving slot positioned within said hook carrying and housing member; two spaced fins each attached to said spring receiving tube at one of its ends and positioned within one of said fin receiving channels at the other of its ends; a latching finger attached to each of said fins attached to said spring receiving tube and positioned in one of said fin receiving channels; a latching hood mounted on said hook carrying and housing member for movement to a hook latching and to a hook unlatching position; a latching brim carried by said latching hood and positioned for cooperating with said hook supporting ledge to latch said fish-hooks upon said fish-hook holder when said latching hood is in its hook latching position; a latching pin carried by said latching hood and positioned for movement in said bayonet slot; and a latching hood latching spring positioned within said spring receiving tube.

14. A safety fish-hook holder consisting of a tubular hook carrying and housing member having hook receiving slots formed therein in the upper part thereof and a leader receiving chamber formed in the lower part thereof there being a plurality of entry and exit slots formed in said leader receiving chamber, the upper end of one of the bounding walls of each of said entry and exit slots and the lower end of each of the other of said bounding walls being curved outwardly; a plurality of external fins formed on said hook carrying and housing member; there being a plurality of cut outs formed in said leader receiving chamber forming open windows therein; there being a hook supporting ledge positioned on said hook carrying and housing member at the floor of said hook receiving slots; there being a pair of

oppositely disposed fin receiving channels formed on the inner face of the wall of said hook carrying and housing member; a fin latching aperture formed in the wall of said hook carrying and housing member near the lower end of each of said fin receiving channel; a spring receiving tube having formed therein at least one bayonet receiving slot positioned within said hook carrying and housing member; two spaced fins each attached to said spring receiving tube at one of its ends and 10 positioned within one of said fin receiving channels at the other of its ends; a latching finger attached to each of said fins attached to said spring receiving tube and positioned in one of said fin receiving channels; a latching pintle formed on each 15 of said latching fingers and positioned within one of said fin latching apertures; a latching hood mounted on said hook carrying and housing member for movement to a hook latching and to a hook unlatching position; a latching brim carried by said latching hood and positioned for cooperating with said hook supporting ledge to latch

said fish-hooks upon said fish-hook holder when said latching hood is in its hook latching position; a latching pin carried by said latching hood and positioned for movement in said bayonet slot; and a latching hood latching spring positioned within said spring receiving tube.

FRANK WOODHEAD.
